TELEPHONE SYSTEM

Original Filed April 28, 1929

UNITED STATES PATENT OFFICE

THOMAS F. CROCKER, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed April 28, 1928, Serial No. 273,544. Renewed October 13, 1930.

This invention pertains to telephone systems in general, but is more particularly concerned with operators' cord circuits and trunk circuits.

5 A telephone switchboard may terminate trunks from a number of different points at which signalling current of the same frequency may or may not be used. To avoid the necessity of providing a ringing current responsive relay in the operator's cords adjusted to respond to the different frequencies of ringing current and adjusted to operate over all the trunks, which may vary widely in characteristics, a separate ringing current 10 responsive relay may be provided for each of the trunks terminating at the switchboard especially adjusted for the trunk, with means controlled by the ringing current responsive relay of the trunk for controlling the ring-down signal in the toll operator's cord. In practice it has been found convenient to render this control over the sleeve conductor of the cord and trunk. When trunks terminate at a switchboard from a number of different 15 points it is also probable that signalling current of different frequencies will be required to signal over the different trunks to control the signals at the distant points. A convenient method of meeting this requirement is 20 to provide each trunk with means for applying ringing current of the particular frequency necessary for that trunk, which means will respond to the operation of a single ringing key in the operator's cord.

25 The object of this invention is the production of a new and improved trunk circuit for a two-way trunk which contains means for controlling the ring-down signal in the operator's cord circuit over the sleeve conductor, and also contains means for applying signalling current over the trunk conductors which means is responsive to the operation of the ringing key in the operator's cord.

30 The particular features of this invention will be described in detail in the following specifications with the aid of the accompanying drawing, in which is shown by means of the usual schematic circuit diagrams a preferred embodiment of the invention.

35 In the drawing, a section of an operator's

cord is shown at O terminating in plug P and provided with the listening key K and the ringing key K². A trunk comprising conductors 4 and 5 is shown terminating at an answering position in the jack J' and having a multiple extending to an auxiliary position and terminating thereat in the jack J².

40 An understanding of the operation of the apparatus involved and the features of the invention may best be obtained from detailed descriptions of the operations involved in the completing of connections. For this purpose, it will first be assumed that a call has been extended from a distant point over the trunk line comprising conductors 4 and 5. To signal the operator at the answering position shown, ringing current is momentarily applied to the trunk conductors at the distant point causing the operation of ringing current responsive relay 10. Relay 10 in operating, removes the normal short-circuit from the signal-control relay 30. Relay 30 thereupon operates over the circuit including contacts 45, and at contacts 32 opens another point in its normal short-circuit so that this relay remains operated after relay 10 restores. Relay 30 in operating, also grounds control conductor 70 at contact 31, thereby closing a circuit for the visual signals V1 and V2 by way of contacts 51 and 41. Visuals V1 and V2 operate to mark the trunk busy. The grounding of conductor 70 also closes the circuit of lamp L1 at the answering position. The lighting of lamp L1 apprises the operator of the incoming call.

45 The operator answers the call by inserting the plug of an idle cord, such as plug P of the cord O, into jack J', and then actuating the listening key K. Inserting plug P into jack J' closes contacts 2 which completes a circuit including contacts 53 for the upper winding of unlocking relay 40. Relay 40 operates and closes a new circuit for visuals V1 and V2 at contacts 42, opens the circuit of relay 30 by separating contacts 45 and closes a circuit for sleeve relay 50 at contacts 44. Relay 30 restores, opening the circuit of lamp L' by removing ground from conductor 70 at contacts 31. The circuit closed for relay 50 includes its two windings in series, contacts 62, sleeve

of jack J1 and plug P, contacts 4, contacts 3, and lamp L. The current flow in this circuit is insufficient to cause lighting of lamp L. Relay 50 operates, however, and opens the circuit of the upper winding of relay 40 by separating contacts 53. At contacts 55 a circuit is prepared for later shunting the lower high resistance winding of relay 50 as will be described subsequently, and at contacts 52 a new circuit is prepared for visuals V1 and V2 which is closed as soon as relay 40 falls back and again closes contacts 41. Relay 40, in restoring also opens the initial energizing circuit of relay 50 at contacts 44, but relay 50, once operated, holds up in series with resistance R2.

After operating the listening key K, the operator may converse with the distance calling operator and then complete the desired connection. Operating key K, by separating contacts 3, inserts resistance R' in the sleeve circuit in place of lamp L. The resistance of R' is considerably higher than the resistance of lamp L so that the current in the sleeve circuit is considerably reduced when key K is operated. Since relay 50 is being energized over its two winding in series, however, it remains operated. After the connection is completed, the operator restores the key K to normal, again placing lamp L in the sleeve circuit.

At the termination of the call, the calling operator receives the usual disconnect signal and then gives the operator at the position shown the ring down signal by again projecting ringing current over the trunk conductors. Again relay 10 responds, causing the operation of relay 30. Relay 30, by grounding conductor 70 at contacts 31, now shunts the lower winding of relay 50. This increases the current in the sleeve circuit sufficiently to cause the lighting of lamp L, thereby signaling the operator. The operator will then either remove the plug P from jack J' or operate key K to converse with the distance calling operator. Should she do the latter, resistance R' is again inserted in the sleeve circuit. This again decreases the current in the sleeve circuit, and since relay 50 is now energized over its upper low resistance winding only, this relay falls back, again closing the circuit for relay 40 at contacts 53. Relay 40 operates and unlocks relay 30 by separating contacts 45, and again closes the circuit for relay 50 over its two windings in series at contacts 44. Relay 50 thereupon re-operates and remains operated, again opening the circuit of relay 40 at contacts 53 whereupon relay 40 again de-energizes. Relay 30 has in the meantime de-energized and again closed contacts 32 so that it will not reenergize when contacts 45 are again closed. It will be noted that the trunk circuit is now in the same condition as it was when the operator initially answered the call.

If the operator removes the plug P from jack J' upon receiving the disconnect sig-

nal, the following operation takes place, remembering that relay 30 is operated at this time and that relay 50 is being held energized over its upper winding. As soon as the tip of the plug P disengages the tip spring of jack J', contacts 2 separate. The following circuit, including the lower winding of relay 40, contacts 54, contacts 52, contacts 41, and the two visual signals V1 and V2 in parallel, becomes effective to cause relay 40 to energize. Relay 40, in energizing, again opens the circuit of relay 30 by separating contacts 45 to allow this relay to restore. Relay 50, of course, also falls back when the plug P is completely removed from jack J', opening the circuit including the two visual signals V1 and V2 in parallel and the lower winding of relay 40 at contacts 54. The trunk circuit of the trunk is thus restored to its normal condition.

To further describe the invention, it will be assumed that the operator at the answering position wishes to extend a connection to the distant point to which the trunk comprising conductors 4 and 5 extends, and chooses this trunk and the cord O to do so. To extend the connection, the toll operator inserts plug P into jack J' and then momentarily operates ringing key K2. Inserting plug P into jack J'; by closing contacts 2, closes a circuit for the upper winding of relay 40. Relay 40 energizes and closes a circuit for visuals V1 and V2 at contacts 42, and closes a circuit for relay 50 at contacts 44. Relay 50 operates as previously described and again causes relay 40 to fall back.

When the operator operates key K2, high resistance R is inserted in the sleeve circuit which sufficiently limits the current in this circuit to cause relay 50 to again fall back. Relay 40 again operates over its upper winding over the circuit including contacts 53 and connects relay 20 and the lower talking conductor at contacts 43. Relay 20 now operates over the circuit including the lower talking conductor, ring of jack J' and plug P to battery through the lower contacts on key K2. Relay 20, in operating, opens the normal ringing bridge including relay 10 across the tip and ring of jack J' at contacts 21 and 25 and connects a source ringing current of the proper frequency to trunk conductors 4 and 5 at contacts 23 and 24.

When key is again restored, relay 50 is again operated and relay 40 is deenergized whereupon relay 20 is again disconnected from the lower talking conductor. Relay 20 then restores to normal. Further operations concerning the completing of the connections need not be described.

Another feature of this invention includes the manner in which a call answered by the operator at the answering position may be transferred to the auxiliary position. To describe the manner in which the transfer

is accomplished it may be assumed that an incoming call over the trunk comprising conductors 4 and 5 have been answered by the operator at the answering position. To transfer the call to the auxiliary position, the operator at the answering position momentarily operates key K'. This causes the lighting of lamp L2 at the auxiliary position to signal the operator thereat, and also closes the circuit of relay 60. Relay 60 operates and at contacts 62 opens the circuit of relay 50, prepares a locking circuit for itself at contacts 63, and prepares a circuit for relay 40 at contacts 41. As soon as relay 50 deenergizes, the circuit of the upper winding of relay 40 is closed at contacts 53. Relay 40 energizes and closes the locking circuit for relay 60 at contacts 42.

When the operator at the auxiliary position inserts the plug of her cord into jack J², relay 50 operates over its two windings in series over the sleeve of jack J² and, as previously described, causes the deenergization of relay 40. Relay 40, by opening contacts 46, opens the locking circuit of relay 60, which relay thereupon restores to normal. It is to be noted that the condition of the trunk circuit is now the same as it was after the operator at the answering position answered the call. Further operations are similar to those previously described.

This completes the description of the operation of this invention. What is considered new and is desired to have protected by Letters Patent is specifically stated in the appended claims.

What is claimed is:

1. In a telephone system, a trunk, a cord circuit and means for connecting it to said trunk, a call signal for the trunk, a cord signal in the cord, a double-wound sleeve relay for controlling said call signal, means for energizing said sleeve relay over both its windings and a non-talking conductor of said cord circuit in series responsive to the connection of the cord circuit to the trunk, and means responsive to the application of ringing current to said trunk before said cord circuit is connected to said trunk for operating said call signal, and responsive to the application of ringing current to said trunk after said cord circuit is connected to said trunk for energizing said sleeve relay independent of one of its windings to increase the current flow in said non-talking conductor to cause the operation of said cord signal.

2. In a telephone system, a trunk comprising talking conductors and a sleeve conductor, a cord circuit, a double-wound sleeve relay for the trunk, a signal in said cord circuit, means for operating said relay over a circuit including both its windings, said sleeve conductor, and said signal in series responsive to the connection of said cord cir-

cuit to said trunk, and means responsive to the application of ringing current to the talking conductors of said trunk for shunting one winding of said relay to increase the flow of current in the sleeve conductor of said trunk to cause the operation of said signal.

3. In a telephone system, a trunk line having talking conductors and a sleeve conductor, a call signal for said trunk line, a cord circuit and means for connecting it to said trunk line, a disconnect signal connected to the sleeve of said cord circuit, a control conductor normally connected to said call signal, means responsive to the application of signalling current to said trunk line for applying a potential to said control conductor to operate said call signal, and means responsive to the connection of said cord circuit to said trunk line for connecting said control conductor to said sleeve conductor so that a subsequent application of a potential to said control conductor will operate said disconnect signal.

4. In a telephone system, a trunk line, a self-locking signal-control relay, means controlled over said trunk line for operating said relay, a cord circuit, a second relay, means for momentarily operating said second relay responsive to the connection of said cord to said trunk line to unlock said signal-control relay, and means for momentarily operating said second relay responsive to the disconnection of said cord from said trunk line to unlock said signal-control relay in case it is operated while the cord circuit is connected to the trunk line.

5. In a telephone system, a trunk line, a self-locking signal-control relay, means controlled over said trunk line for operating said relay, a cord circuit, a double-wound unlocking relay, means responsive to the connection of said cord circuit to said trunk line for momentarily closing a circuit including one winding of said unlocking relay to cause it to operate and unlock said signal-control relay, and means effective when said cord circuit is disconnected from said trunk line for momentarily closing a circuit including the other winding of said unlocking relay to cause it to operate and unlock said signal-control relay in case it is operated after the cord circuit is connected to the trunk line.

6. In a telephone system, a trunk line, a self-locking signal-control relay, means controlled over said trunk line for operating said relay, a cord circuit, an unlocking relay, means for momentarily operating said unlocking relay responsive to the connection of said cord circuit to said trunk line to unlock said signal-control relay, means controlled at will for causing a reoperation of said unlocking relay to unlock said signal-control relay in case it is operated while the cord circuit is connected to the trunk line, and means

for causing a reoperation of said unlocking relay responsive to the disconnection of said cord circuit from said trunk line to unlock said signal-control relay in case it is operated 5 while the cord circuit is connected to the trunk line.

7. In a telephone system, a trunk line, a self-locking signal-control relay, means controlled over the trunk line for operating said 10 relay, a cord circuit, a double-wound unlocking relay, means for momentarily closing a circuit including one winding of said unlocking relay responsive to the connection of said cord circuit to said trunk line to cause it to operate and unlock said signal-control relay, a key in said cord circuit for causing a reoperation of said last means to unlock said signal-control means in case it is operated 15 while said cord circuit is connected to said trunk line, and means effective when said cord circuit is disconnected from said trunk line for momentarily closing a circuit including the other winding of said unlocking relay to cause it to operate and unlock said signal-control relay in case it is operated 20 while said cord circuit is connected to said trunk line.

8. In a telephone system, a trunk line, a cord circuit, a double-wound relay for the 25 trunk, means for establishing an operating circuit for said relay including its two windings in series when said cord circuit is connected to said trunk line, means controlled at will over said trunk line for shunting one 30 winding of said relay, means in said cord circuit for limiting the current flow in said circuit sufficiently to cause said relay to restore providing one winding of said relay is shunted, and other means in said cord circuit for 35 limiting the current flow in said circuit sufficiently to cause said relay to restore when energized over its two windings in series.

9. In a telephone system, a trunk, a cord 40 circuit and means for connecting it to said trunk, a sleeve relay for the trunk responsive to the connection of said cord circuit to said trunk, a signalling relay for applying signalling current to said trunk, a key in said cord circuit, contacts on said key for causing the 45 release of said sleeve relay when the key is operated, means responsive to the release of said sleeve relay for connecting said signalling relay to one talking conductor of said trunk, and contacts on said key for closing an energizing circuit including said one talking conductor for said signalling relay when the key 50 is operated.

10. In a telephone system, a trunk line, comprising talking conductors and a sleeve 55 conductor, means for extending a connection to said trunk, a sleeve relay connected to said sleeve conductor, means responsive to the extension of a connection to said trunk for establishing a flow of current in said sleeve conductor to operate said relay, a signalling

relay for applying signalling current to said talking conductor, means for decreasing the flow of current in said sleeve conductor to restore said sleeve relay, means responsive to the restoration of said sleeve relay for connecting said signalling relay to one of said talking conductors, and means for then causing the operation of said signalling relay. 70

11. In a telephone system, a trunk line terminating in two jacks, a signal for each jack, a transfer relay, a sleeve relay connected to the first jack through contacts on said transfer relay and connected to the second jack directly, means for operating the signal of the first jack when a call is extended over said trunk line, means for operating said sleeve relay when the call is answered via the first jack to restore the signal thereof, a key for operating the signal of said second jack and for operating said transfer relay to cause said sleeve relay to restore, a locking circuit for said transfer relay, and means controlled by said sleeve relay for opening said locking circuit to cause said transfer relay to restore responsive to the answering of the call via 80 said second jack. 75

12. In a telephone system, a trunk comprising talking conductors and a sleeve conductor, a cord circuit adapted to be connected to said trunk, a key for said cord circuit, a relay for connecting ringing current to said trunk, and circuit connections including one talking conductor and the sleeve conductor of the trunk and said key for operating said relay. 95

13. In a trunk terminating in two jacks, a signal for each jack, a key for the first jack, a sleeve relay normally connected to both jacks, means for operating the signal at the first jack responsive to the extension of a call over the trunk, and means for operating the signal at the second jack and for disconnecting the sleeve relay from the first jack responsive to the operation of said key. 100

14. In a trunk terminating in two jacks with individual signals for the jacks, a key for the first jack, a sleeve relay normally connected to both jacks, means for actuating the signal at the first jack responsive to the extension of a call over the trunk, means for actuating the signal at the second jack and for disconnecting the sleeve relay from the first jack responsive to the operation of said key, and means for deactuating both said signals responsive to the answering of the call from the second jack. 110

15. In a trunk circuit terminating in an answering jack, a signal control relay operated responsive to a call over the trunk, an unlocking relay for controlling said signal relay, a third relay, a key, contacts on the jack for operating said unlocking relay responsive to the answering of a call, and contacts on said third relay for operating said 125 120 130

unlocking relay responsive to the actuation of said key.

16. A trunk terminating in a jack, a visual signal, two relays, circuit connections including contacts on the jack for operating the first of said relays effective when the second relay is normal, and circuit connections for operating the first of said relays in series with said signal effective when the second relay is actuated.

17. In a telephone system, a trunk terminating in a jack, a cord circuit including a plug adapted to co-operate with the jack, a relay for the trunk said relay having two windings, means for momentarily operating the relay over a circuit including one winding responsive to the insertion of the plug in the jack, and means for momentarily reoperating said relay over a circuit including the other winding responsive to the withdrawal of the plug from the jack.

18. In a telephone system, a trunk terminating in a jack, a cord circuit including a plug adapted to co-operate with the jack, a relay and a visual busy signal for the trunk, means for momentarily operating the relay over a circuit including contacts on the jack responsive to the insertion of the plug in the jack, and means for momentarily reoperating said relay in series with said signal responsive to the withdrawal of the plug from the jack.

19. In a telephone system, a trunk circuit including a sleeve relay, two windings for the relay, said windings being connected in series to a source of current through a resistance, means responsive to the answering of a call over the trunk for momentarily shunting said resistance and for operating said relay over the two windings in series, and means subsequently controlled over the trunk for shunting said resistance and one of said windings and for maintaining said relay operated over the other winding.

20. In a telephone system, a trunk and means for extending a call thereover, means for answering the call, a sleeve relay for the trunk normally connected to ground through a resistance, and means responsive to the answering of the call for momentarily short circuiting said resistance to complete an operating circuit for said relay.

21. In a telephone system, a trunk, means for extending a call over the trunk, means for answering the call, a battery, a relay in said trunk, a sleeve conductor for the trunk extending through the winding of said relay and a resistance in series therewith to one pole of said battery, and means responsive to the answering of a call for connecting the other pole of said battery to said sleeve conductor and for momentarily short-circuiting said resistance to operate said relay.

22. In a telephone system, a trunk terminating in a jack, a plug adapted to co-operate

with the jack, a sleeve relay for the trunk, an operating circuit for said relay closed momentarily responsive to the insertion of the plug in the jack, and a holding circuit for said relay including a normal connection to a source of current through a resistance.

23. In a telephone system, a trunk line including a sleeve conductor, a relay connected to said conductor, an operator's link, a signal for said link, means responsive to the connection of the link to the trunk line for connecting said signal and said relay via said sleeve conductor to operate the relay, means for limiting the current flow over said sleeve conductor to prevent the operation of said signal, a relay normally connected to the talking conductors of the trunk line adapted to be disconnected therefrom when ringing current is applied to the near end of the trunk line and to operate responsive to the application of ringing current to the distant end of the trunk line, and means controlled by said second relay for increasing the current flow over said sleeve conductor to operate said signal.

24. In a telephone system, a trunk line terminating in a manual jack, a relay connected to the sleeve of said jack, a cord circuit including a plug adapted to cooperate with said jack, a signal connected to the sleeve of said plug, means responsive to the connection of the cord to the trunk line for establishing a current flow over said sleeves to operate only said relay, a relay normally connected to the trunk line adapted to be disconnected therefrom when ringing current is applied to the near end of the trunk line and to operate when ringing current is applied to the distant end of the trunk line, and means controlled by said relay for increasing the current flow over said sleeves to operate said signal.

25. In a telephone system, a trunk line comprising talking conductors terminating in a manual jack, a relay connected to the sleeve of said jack, a cord circuit including a plug adapted to cooperate with said jack, means responsive to the connection of the cord with the trunk line for establishing a flow or current over the sleeves of the plug and jack to operate said relay, a source of signalling current, means in the cord circuit for decreasing the flow of current over said sleeve to release said relay, and means effective on the release of said relay for disconnecting the talking conductors from said jack and for connecting them to said current source.

26. In a telephone system a trunk line comprising two talking conductors and a non-talking conductor an operator's link circuit and means for connecting it to said trunk line, a source of signalling current, a relay for connecting said two talking conductors to said current source, and means controlled from said link circuit over one of said talk-

ing conductors and said sleeve conductor for operating said relay.

27. In a telephone system, a trunk line comprising two talking conductors, an operator's link circuit and means for connecting it to said trunk line, a source of signalling current, a relay for connecting said talking conductors to said current source, means controlled from said link circuit for connecting said relay to one of said talking conductors at will, and means controlled over said one talking conductor for operating said relay.

In witness whereof, I hereunto subscribe my name this 25th day of April, A. D. 1928.

15 THOMAS F. CROCKER.
